UNITED STATES PATENT OFFICE.

ARTHUR HANTSCH, OF LINDEN, NEW JERSEY.

CALCULATING MACHINE.

1,077,274.

Specification of Letters Patent.

Patented Nov. 4, 1913.

Application filed July 31, 1912. Serial No. 712,427.

To all whom it may concern:

Be it known that I, ARTHUR HANTSCH, a citizen of the German Empire, and a resident of Linden, Union county, New Jersey, have invented certain new and useful Improvements in Calculating Machines, of which the following is a specification.

This invention relates to calculating machines and refers in particular to improvements in the setting up mechanism and the mechanism for operating the tens wheels.

The setting up mechanism in calculating machines generally comprises some manually operated means for setting up the multiplicand or divisor or other factor as the case may be whereby the tens wheels are properly positioned for "carrying over" the calculation from feed drum to feed drum. The operation of setting up consists in moving a sliding member into a given position opposite the cipher which is to be used. Thus for instance if the calculation to be executed is 7893×375 , the ciphers 7, 8, 9 and 3 must be "set up" in their respective columns. To this end the aforesaid sliding member, generally a projecting knob, is moved from zero into a position opposite 3 in the unit column, the adjacent knob is placed opposite 9 in the tens column, the next adjacent knob is placed opposite 8 in the hundreds column, and so forth. The placing of the knobs or buttons or other members into their various positions in turn operates the corresponding tens wheels as is well known. Heretofore the members in each of the columns have been placed in a single row or column and consequently very close together, hence mistakes in placing the knob or other operating member occurs frequently and is not easily seen. It should be noted that this member may be moved back and forth at will, so that an accidental touch of the operator easily displaces the knob hence the tens wheel operated thereby and incorrect results follows of course.

One of the objects of this invention is to so arrange the tens wheel operating member, that the cipher wanted may be set up by a movement in one direction only and to so arrange the operating connections between the manually operated slide member and the tens wheel actuated thereby, that the slide member is moved a distance twice as great as the movement of the tens wheel.

Further, I provide a simple means for can-

celing an incorrectly set up cipher. Another advantage gained by the operating member as constructed according to my invention is that I am able to place the ciphers in two columns or rows on the member itself, hence am able to make the ciphers very large and easily readable.

Other objects of the invention and consequent advantages will appear.

In the drawings illustrating the preferred form of my invention Figure 1 is a plan view of a calculating machine embodying my invention. Fig. 2 is a fragmentary view showing the tens wheel operating or set up member. Fig. 3 is a transverse sectional view showing the construction of the set up member in elevation and the means for operating the tens wheel. Fig. 4 is a similar view with parts omitted. Fig. 5 is a right hand end view of Fig. 3. Fig. 6 is a plan view of the set up member. Fig. 7 is a perspective view of a bracket used in the construction illustrated. Fig. 8 is a detail view of the tens wheel and its actuating fork.

In the drawings the reference numeral 1 represents the framework of the machine.

2 is the slide rule. 3 and 4 the cover plates.

5 is the feed drum and 6 the tens wheel. 85 There is a setting up mechanism for each tens wheel for positioning the latter to be engaged by a tooth of the proper length on the feed drum. To this end the tens wheel is mounted to slide on a square shaft 7. 90 The setting up mechanisms are alike for each tens wheel so only one need to be described.

8 designates a sliding member provided with a rack 9 and which carries a fork 10 which engages the tens wheel 6, Fig. 8. The sliding member is supported and guided in a bracket 11, as best seen in Fig. 5, and journaled in two adjacent brackets 11 is a shaft 12 to which is secured two gears 13 and 14. The latter is twice the diameter of the former. Gear 13 meshes with rack 9 and gear 14 is in engagement with another rack 15 which is part of the finger slide 16, which is formed as a fork of which the said rack 15 forms the lower branch—below the plate 3—while the slide 17 forms the upper branch—above the plate 3. The slide and the rack are joined at 18. The inside shoulder 19 forms a stop which abuts the front edge 20 of the plate 3 when the slide is in neutral position. The rack 15

is guided in ways 21 suitably formed on the underside of the plate 3. A spring 22 tends to keep the slide in zero or neutral position, which is as shown in Figs. 1, 2 and 3. The upper face 23 of the rack 9 is provided with numbers from 0 to 9 which appear through the aperture 28 in the plate 3 as the numbers are set up. The slide 16 is formed into two column pieces 24 and 25 which together carry numbers from 0 to 9, alternating the even numbers on the one column and the uneven numbers on the other column. The slide members are impressed on inclined surfaces 26 between suitable finger stops 27. 5

15 28 is a pawl which is pivoted on a suitable bearing 29 secured to the cover 4 and kept in engagement with the gear 13 by a spring 30. 31 is a push member having a button 32. When the latter is pressed down the pawl is disengaged from the gear 13. All the pawls 31, one for each setting up mechanism, may be lifted out of engagement with the gears 13 by means of the shaft 33, which is flattened where the pawls 25 pass over it as shown at 34. The shaft 33 extends across the machine as seen in Fig. 1 and is rotated or operated by a push button 35 connected to the shaft by a crank arm 36 in a well known manner.

30 Normally the setting up mechanism is in the position shown in Figs. 1 to 3. When it is desired to set up a multiplicand as for instance "7893" the operator puts his forefinger on cipher "3" on the slide 16 in the 35 unit column 40, Fig. 1, and pulls back the slide 16 until his finger touches the rear edge 45 of the cover 4, and the cipher "3" will appear in unit column aperture 28. Next the operator puts his finger on the cipher 40 "9" on the slide 16 in the tens column 41 and pulls that back and then repeats the operation for the hundreds column 42 and the thousands column 43. By means of the above described construction it follows that 45 as the slides 16 are pulled forward, toward the operator, the respective tens wheels have been moved rearward into their proper positions to be engaged by the feed drums, and as shown for instance in Fig. 4. If an 50 error is made, which can readily be detected through the apertures 28, the operator corrects the "set up" by pushing the button 32. Or if all the "set ups" are erroneous they may be canceled by operating the push button 35. The advantages of this construction are quite obvious. The operator is able to set up the number wanted by comparatively long quick strokes of the sliding member by a natural movement toward him.

55 60 The movement is certain and sure as no matter which figure is to be set up the movement is always stopped by the edge of the cover 4 and the pawl 28 in coöperation with the rack prevents a movement of an incomplete length. Another advantage is ob-

taigned by having the two gears, one twice the size of the other, as thereby the operator pulls the slide twice the distance of the movement of the tens wheel, hence can operate with greater certainty and also the 70 numbers on the slide can be made larger. After the operation of the setting mechanism, the crank 50 and slide 2 are operated in the usual manner in calculating machines of the type disclosed in British Patent Number 13504 of 1851. If the operator is an expert the setting up of the numbers can be done very quickly in that the finger stops 27 form means for guiding the tips of the fingers hence the operator can use several 80 fingers at once with the touch method and need hardly look at the figures on the finger slides, and after the desired number has been set up, the figures on the rack 15 clearly indicate whether or not the operation has been correct as each figure may be seen at a 85 glance through the apertures or windows 28 in the cover plate.

Details in the construction set forth may of course be varied within the principle of the invention and the scope of the claims.

I claim:

1. In a setting up mechanism for calculating machines, the combination of a cover plate, a tens wheel, a finger slide movably supported on said cover plate for operating said tens wheel, said finger slide comprising a member provided with the numbers 0-9 below the said cover plate but adapted to appear through a window in the same, said finger slide being arranged to be moved manually in one direction and to be stopped always at the same given point irrespective of the length of the movement of said slide as indicated by the number appearing through said window in the cover.

2. In a setting up mechanism for calculating machines the combination of a fixed support, a tens wheel, a finger slide for operating the same and movably supported on the said fixed support, said finger slide being provided with a set of exposed numbers 0-9 arranged in two columns and a second set of numbers 0-9 below the said fixed support but adapted to appear single through a window in the latter to indicate the position of the said tens wheel when the said finger slides is operated.

3. In a setting up mechanism for calculating machines, the combination of a tens wheel, a rack operatively connected to the latter, a rotatable shaft, a gear on the latter in mesh with the said rack and a finger slide for operating said gear and rack to cause an axial movement of said tens wheel.

4. In a setting up mechanism for calculating machines, the combination of a tens wheel, a rack operatively connected to the same, a shaft, a gear on said shaft in mesh with the said rack, a second gear on said

- shaft, a finger slide having a rack in mesh with said second gear, which latter is of a greater diameter than the first named gear whereby when said slide is moved a given 5 distance, the said tens wheel is moved axially a less distance to place the same in a given position.
5. A finger slide for setting up the product numerals in calculating machines comprising a forked member, the upper branch of said forked member bearing the numerals 0-9 arranged in two columns, the lower branch of said forked member bearing the numerals 0-9 arranged in a single column.
- 10 6. A finger slide for setting up the product members in calculating machines comprising a forked member, the upper branch of said member bearing the numerals 0-9 arranged in a double column and having finger stops placed between each two succeeding numerals, the lower branch bearing the numbers 0-9 arranged in a single column.
- 15 7. A finger slide for setting up the product numerals in calculating machines comprising a single member forming an upper and a lower branch, the upper branch being slotted and bearing the numerals 0-9 arranged in two columns, the even numbers on one side of the slot, the uneven number 20 on the other side of the slot, and having finger stops intervening between each two succeeding numerals, the lower branch of said member bearing the numbers 0-9 arranged in a single column and appearing 25 through the slot in the upper branch.
- 30 8. In a setting up mechanism for calculating machines the combination of a cover plate having a window, a finger slide mounted to slide on said cover plate and having 35 one set of exposed numbers 0-9 and formed
- with finger stops between each two succeeding numerals for operating said slide, the latter having another set of numbers 0-9 below said cover plate adapted to be seen singly through said window, a tens wheel 40 and means operated by the finger slide whereby, when said finger slide is moved a distance determined by the position of a given one of the exposed members, the said tens wheel is moved into a corresponding 45 given position indicated by the appearance of one of the members below the cover plate through said window and corresponding to the said given number of the exposed numbers.
- 50 9. In a setting up mechanism for calculating machines the combination of a tens wheel, a finger slide adapted to be operated manually in one direction to place said tens wheel in a given position, operating connections between said finger slide and said tens wheel comprising a rack on said finger slide, a second rack in operative engagement with the said tens wheel, gears interposed between said racks and in engagement with both of them, a pawl in engagement with one of the said gears, a push button for disengaging said pawl from the said one gear and means for automatically moving the said finger slide in the opposite direction to place the said tens wheel in zero position when the said push button is operated.
- 55 Signed at New York, N. Y., this 26th day of July 1912.

ARTHUR HANTSCH.
